United States Patent

Des. 242,484
Patented Nov. 23, 1976

242,484

PHONOGRAPH HOUSING

Jack Friedman, New York, N.Y., assignor to
L.J.N. Toys, Ltd., New York, N.Y.

Filed Apr. 3, 1975, Ser. No. 564,694

Term of patent 14 years

Int. Cl. D14—01

U.S. Cl. D56—4 R

FIG. 1

FIG. 4

FIG. 2

FIG. 3

FIG. 5

FIG. 6

FIG. 1 is a front and left side perspective view of a phonograph housing showing my new design;

FIG. 2 is a top plan view;

FIG. 3 is a front elevational view;

FIG. 4 is a right side elevational view;

FIG. 5 is a rear elevational view; and

FIG. 6 is a bottom plan view.

I claim:

The ornamental design for a phonograph housing, as shown and described.
